UNITED STATES PATENT OFFICE.

WILLIAM JOSEPH McDERMOTT, OF KANDIYOH, MINNESOTA.

DESIGN FOR A TREAD-POWER WHEEL.

SPECIFICATION forming part of Design No. 33,559, dated November 13, 1900.

Application filed September 15, 1900. Serial No. 30,181. Term of patent 7 years.

To all whom it may concern:

Be it known that I, WILLIAM JOSEPH McDERMOTT, a citizen of the United States, residing at Kandiyohi, in the county of Kandiyohi and State of Minnesota, have invented and produced a certain new and useful Design for a Tread-Power Wheel; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to a new design for a tread-power, and the features of the design are clearly illustrated in the accompanying drawings, in which I have shown, in—

Figure 1, a rear elevation of the motor-wheel, and in Fig. 2 a central vertical sectional view.

Reference now being had to the details of the design by letter, A designates a circular-

outlined wheel with radiating spokes B. At the outer end of each spoke is an angular raised portion B', which projects beyond the circumference of the wheel and has a contracted projecting portion B² on its outer face. On the outer face of each spoke is a longitudinal projecting rib D. A radiating series of rods having obtuse-angled ends are arranged about the central hub portion of the wheel, and about the circumference of the wheel is a right-angled flange having a series of slits F about its circumference. 35

Having thus described my invention, what I claim is—

The design for a tread-power wheel, substantially as shown and described.

In testimony whereof I affix my signature in presence of two witnesses.

WILLIAM JOSEPH McDERMOTT.
